UNITED STATES PATENT OFFICE.

PAUL LOUIS FRANCOIS HIPPOLYTE CHAUSSINAND, OF ST. DIZIER, FRANCE.

MASSAGING APPARATUS.

1,387,687.

Specification of Letters Patent. Patented Aug. 16, 1921.

Application filed April 2, 1913. Serial No. 758,418.

(GRANTED UNDER THE PROVISIONS OF THE ACT OF MARCH 3, 1921, 41 STAT. L., 1313.)

To all whom it may concern:

Be it known that I, PAUL LOUIS FRANCOIS HIPPOLYTE CHAUSSINAND, a citizen of the French Republic, and resident of St. 5 Dizier, Haute-Marne, France, have invented a certain new and useful Improvement in Massaging Apparatus, (for which I have filed an application in France, April 2, 1912, Patent No. 442,035,) of which the following 10 is a specification.

This invention relates to a vibratory massage apparatus and has for its object to provide an improved construction of such apparatus which can be operated manually or 15 mechanically and can be used for effecting and combining different methods of massage and for friction treatment, the massaging surface being divided in to a large number of small elements each operating locally and 20 permitting of multiplying the vibratory power for a given period.

One embodiment of the invention is illustrated in the accompanying drawing by way of example, the apparatus shown being manually 25 operable.

In the drawings Figure 1 is a vertical section of the apparatus; Fig. 2 is a section on the line A—A of Fig. 1; Fig. 3 is a vertical section to enlarged scale of the upper part 30 of a slightly modified type of apparatus showing the percussion members and their operating means, in combination with the friction treatment apparatus.

Fig. 4 is a plan of the apparatus showing 35 another arrangement of the fingers in anular or circular series.

The apparatus comprises a casing 1 in the form of a box or frame, provided with a handle 2 and inclosing any suitable operating means, for example, a double train of 40 gear wheels 3, 3, 3', 3', operated by an external crank 4, the movement being transmitted by bevel wheels 6, 6 to the vertical shaft T, which carries the vibratory driving members as will be hereinafter described. 45 A fly wheel 5 is mounted on one of the shafts, preferably that which revolves most rapidly *i. e.* in the case shown, on the shaft T.

The casing 1 is provided at its upper end 50 with a box 7 comprising at its upper end two partitions 8 and 9 bolted together and provided for example, in circular concentric lines (Figs. 1 and 2) with holes permitting the passage of the percussion members 10 called "fingers." These fingers, (Fig. 3)

guided by the partitions 8, 9 are each provided with a collar 11 at the lower end and a spring 12 interposed between these collars and the upper wall 9, and acting continuously to depress or retract the finger. A 60 rubber washer or the like 10' is interposed between the collar 11 and the lower partition 8 to absorb shocks and prevent noise when the finger strikes on its seat under the action of its spring. The rounded end of each 65 finger may be provided with grooves or channels dividing the massaging action which further permits of almost completely juxtaposing the fingers.

Centrally, is arranged a rod 13 guided in 70 a square portion 14 in the lower partition 8 in such manner as to be capable of displacement in an axial direction but not in a rotary direction, and forced continuously in a downward direction by a spring 15 but 75 limited in this movement by a collar, bolt or the like 32 bearing on the upper partition 9. This axial rod 13 and the finger like members 10, arranged concentrically are adjustably controlled by the following arrangement:

On the vertical driving shaft T is keyed in such manner as to be able to slide longitudinally, a member forming a cross piece 18 with one or more arms 19, 19' each of 80 these arms having a roller 20, 20', which moves along the corresponding circular row of fingers in a plane transverse or substantially perpendicular to the longitudinal thrust of said fingers. In the embodiment 85 shown there are two circular rows of fingers and consequently two roller carrying arms 19, 19', the longer of which is made lighter than the shorter so as to balance the effects of the centrifugal force. When the cross 90 piece 18 rotates, the rollers 20, 20', raise the fingers preferably one by one successively and alternately on opposite sides of the central axis, the fingers of the two rows being for this purpose arranged in staggered relation as shown in Fig. 2. It will be understood that other arrangements might be used without departing from the spirit of 95 the invention.

The central rod 13, is given a vibratory 100 movement by the following arrangement:

This rod has at its lower end a member 22 in the lower face of which are provided radial grooves forming inclined cam surfaces 22'. This member 22 is arranged 105

above a similar member 23 carried by the cross piece and the cams 23' of which are arranged opposite the first. When the cross piece rotates the part 22 integral with the rod 13 which cannot rotate on account of its square portion 14 but may move vertically (being constantly depressed by its spring 15) is raised by the cams and carries in its movement the rod 13. Then the cams 22' of the part 22 fall back into the recesses in the lower rotating member thus producing a vertical vibration of the rod 13, the frequency of which depends on the number of cams in the plates 22 and 23.

15 The amplitude of the percussions or thrusts of the central rod and of the fingers 10 may be regulated in such manner as to permit at will light massage, or massage by percussion owing to the possibility of longitudinal adjustment of the cross piece on its driving shaft T. To this end this latter is formed, for example, with a vertical slot 25 (Fig. 3) and the cross piece 18 is provided with a key or stop screw 26 in such manner as to permit an adjusting movement of the cross piece along its rod, while maintaining the two members connected in rotation. The position of the cross piece on the rod is regulated by means of any suitable device, 30 for example by means of a fork 27 on which rests a part 28 of the cross piece and permitting of the raising of this latter more or less, although it may be itself adapted to be moved upward or, as shown, it may be moved transversely, its arms being in that case arranged in the form of wedges, the lower face bearing on the collar 29 of the driving shaft T, and the upper face supporting the cross piece by its part 28. In 35 the example shown, the fork 27 is screwed on a threaded rod 39 which may rotate in the frame 1 or in the box 7, said rod being constantly pressed inward by the spring 30 and adapted to be rotated by the head 39' of the screw. On rotation of the threaded rod by 40 means of this head 39', the fork is moved transversely in either direction. It may be moved for example, outwardly to allow the cross piece to drop until the rollers 20 no longer strike the peripheral fingers 10 and until the cams of the plate 22 of the cross piece are no longer in engagement with the cams of the plate of the rod 13. By regulating the position of the cross piece it is 45 thus possible to regulate at the same time the amplitude of the percussions or thrust movements of the fingers, and that of the central rod, this latter being intended to carry various massaging members as will be explained later on.

50 In some cases it is of importance that one should be able to operate the fingers and the central rod at the same time or the fingers alone or the central rod alone. For 55 this purpose the central rod may be thread-

ed on its outer end at 17, and instead of a collar has a pinion 32^a which can be operated from the side of the casing and bears against the upper partition 9 of the casing 12 in such manner as to permit variation of the lowest position (recoil position) 70 of the central rod in order to separate the two cam members or to bring them into engagement.

A convenient and compact arrangement 75 for effecting rotation of the pinion comprises a key or shaft 32' extending transversely of the upper side of the casing, its inner end lying in a depression or recess 9' in the upper partition 9, and being provided 80 with a worm arranged to engage said pinion. In the drawing the central rod is shown in lowered position and the two cam members are in engagement. Upon suitable rotation of the pinion 32^a the rod 13 is raised 85 and is locked (the cams not being in engagement) while the fingers continue to operate. By moving the forked wedge 27 outwardly to lower the cross piece 18 and thus to prevent contact of the rollers 20, 20', with 90 the fingers, and by turning pinion 32^a so as to lower cam member 22 of the central rod into operative position, the central rod only will be subjected to vibratory movement, while the non-central series of fingers remain idle.

The central rod is most conveniently tubular as shown in Fig. 3 and is internally threaded for attachment of different massage instruments. Thus the central rod may 100 receive a screw 32^b provided with a round head, the screw forming a central finger similar to the peripheral fingers; or the central rod may be provided with a rubber disk 33 to which is secured a ring 34 consisting 105 of cloth which may be moistened with a liquid. A suitable method of attachment of this ring consists in providing the rubber disk 33 with a flange 33' forming a kind of open pocket in which the ring can be introduced. The fingers 10 operate first across the rubber disk and combine their effects with that of the liquid to produce a medicinal friction. The rubber pocket can be also used without any packing as a simple 110 absorbing device operating without moisture. In place of fixing the central metallic disk of the rubber pocket on the rod 13 by means of a screw engaging the internal thread of this rod as shown, this central 115 metal piece may be formed as a screw threaded on the outer thread in such manner to replace the collar or nut 32 intended for limiting the movement of this rod 13.

120 It will be understood that various modifications may be made without departing from the scope of the invention. In particular the arrangement of the fingers may be modified at will; the cross-bar may have two or four arms; regulation of the axial posi- 125 130

tion of the cross-bar can be effected by other means than those indicated, etc. An essential advantage of the invention consists in the subdivision of the vibrating effect 5 among a large number of small separate elements operating simultaneously or preferably alternately. This permits of multiplying considerably the frequency of vibrations and their amplitude and energy over a given 10 space, since in this arrangement action takes place at the same time only on small separate parts which permits of better contact than with the large single massaging surfaces used hitherto.

15 Having described my invention what I claim and desire to secure by Letters Patent of the United States is:—

1. A vibratory massaging apparatus comprising in combination with a driven shaft, 20 a cross-member carried thereby, rollers mounted on said cross-member, and a series of fingers actuated by said rollers, as and for the purpose set forth.

2. A vibratory massaging apparatus comprising in combination with a driven shaft, 25 a cross-member carried thereby, rollers on said cross-member, a series of fingers actuated by said rollers, a rod, and means whereby said rod may be vibrated by said shaft, 30 as and for the purpose set forth.

3. A vibratory massaging apparatus comprising in combination with a driven shaft, a cross-member carried thereby, and adapted to rotate therewith, rollers provided on 35 said cross-member, a series of fingers actuated by said rollers, and means for raising and lowering said cross-member on said shaft, as and for the purpose set forth.

4. A vibratory massaging apparatus comprising, in combination with a driven shaft, 40 a cross-member carried thereby, rollers on said cross-member, a series of fingers actuated by said rollers, a rod, means whereby said rod may be vibrated by said shaft, and 45 means for limiting the movement of said rod, as and for the purpose set forth.

5. A vibratory massaging apparatus comprising, in combination with a driven shaft, a cross-member carried thereby and adapted 50 to rotate therewith, rollers mounted on said cross-member, a series of fingers actuated by said rollers, means for limiting the movement of said rod, and a rubber pocket carried by said rod said pocket arranged 55 over said fingers, as and for the purpose set forth.

6. Massaging apparatus comprising a massage member mounted for thrust movement, means arranged to travel in a plane transverse to the direction of thrust and 60 adapted to engage and thereby to actuate said massage member and means for varying the extent of the thrust movement thereby imparted to said massage member.

7. Massaging apparatus comprising a plurality of massage members mounted in substantially circular series for longitudinal thrust movement, and means arranged to move transversely to the direction of thrust so as to engage said massage members successively and thereby to actuate the same. 70

8. Massaging apparatus comprising a plurality of massage fingers disposed about a central axis and mounted for longitudinal thrust movement substantially parallel to 75 said axis, and means arranged to turn about said axis and to engage the ends of said fingers successively to actuate the same.

9. A vibratory massaging apparatus comprising the combination, with a driven shaft, 80 and an arm revoluble therewith and carrying an actuating roller, of a plurality of vibratory elements arranged to be actuated by said roller.

10. A vibratory massaging apparatus comprising the combination, with a driven shaft and a cross member revoluble therewith, of a plurality of vibratory elements arranged in annular series around the axis of said shaft, said cross member being adapted, 90 when revolved, to actuate said vibratory elements successively and alternately on opposite sides of the shaft axis.

11. A vibratory massaging apparatus comprising the combination, with a plurality of 95 individually operable vibratory elements in substantially annular arrangement, of means revoluble to engage said elements successively to operate the same.

12. A vibratory massaging apparatus comprising the combination, with a massaging surface consisting of a relatively large number of individually operable small vibratory elements, of means operable to engage and thereby to vibrate said elements successively. 100 105

In testimony whereof I have signed my name to this specification in the presence of two subscribing witnesses.
